S. H. KNAPP

MILKING MACHINE VALVE

Filed Sept. 12, 1922

FIG. 1.

FIG. 2.

FIG. 3.

Inventor:

S. H. Knapp

By

Langme, Parry, Ward & Langme

Atys.

UNITED STATES PATENT OFFICE.

SYDNEY HERBERT KNAPP, OF GREYTOWN, WELLINGTON, NEW ZEALAND.

MILKING-MACHINE VALVE.

Application filed September 12, 1922. Serial No. 587,817.

To all whom it may concern:

Be it known that I, SYDNEY HERBERT KNAPP, a citizen of the Dominion of New Zealand, and a subject of the King of Great Britain and Ireland, residing at Humphries Street, Greystown, in the Provincial District of Wellington, New Zealand, have invented certain new and useful Improvements in Milking-Machine Valves, of which the following is a specification.

This invention relates to that class of valves used on milking machines for the purpose of preventing admission of air to the system, when a teat cup or cups become dislodged from or come off the teat of a cow.

The object of the present invention is to provide an improved form of valve, which is capable of being used for purposes other than, and in addition to that above mentioned.

According to the invention, the valve comprises a valve casing provided with directly opposite nipples adapted to be inserted in or attached to milk tubes. The passages through said nipples can be of the same diameter.

The hollow plug in which a ball is housed is tapered and has directly opposite ports one larger in diameter than the other, the larger port having a bar wire or the like secured across same to prevent the ball seating itself in and closing the said port. The smaller port has an internal seating formed around it for said ball.

The plug also has projecting therefrom a pin which works between stops of the casing, so as to limit the turning movement of the plug in the casing to a half turn.

Projecting from the plug is a spring 40 pressed ball adapted to engage in a circular groove inside the casing.

The plug which is capable of being drawn out of the casing from the top, is retained therein while in use by the engagement of the spring pressed ball in said circular groove, said engagement however not being sufficient to prevent the plug from being removed, when desired.

A groove in the outer surface of the plug 50 connects or extends from one port to the other port therein, while a further groove

extends from said connecting groove to the bottom or smaller end of the plug.

The plug is provided with a handle or thumbpiece, whereby it can be operated. 55

An inverted cap or ball container, open to atmosphere through ports, screws on to the lower end of the casing, the ball held in said cap or container being adapted to seat itself in and close the lower end of the 60 casing on the air being exhausted from the interior of the plug, and or the casing.

A cross piece fitted in the lower end of the plug has projecting downwards therefrom a spring pressed pin against which the 65 ball in the inverted cap or container is held so as to compress the spring actuating said pin, when said ball is seated in the lower end of the casing.

The inverted cap or container open to atmosphere and the ball therein, are provided for the purpose of ensuring that air will get behind the ball in the plug, on the breaking down of the vacuum in the latter by a cup or cups coming off a teat or teats 75 as when such happens the ball in the cap or container, assisted by the spring operated pin drops and opens the lower end of the casing to atmosphere thereby ensuring that the ball in the plug will be forced into its 80 seating around the port in the plug and thereby prevent the entrance of air to the system.

The grooves in the plug are provided to ensure the ball in the cap or container, coming under the effects of vacuum when required so as to seat itself in the lower end 85 of the casing and prevent the entrance of air to the latter and the plug.

The drawings herewith illustrate the invention:—

Figure 1 is a sectional elevation of the valve.

Figure 2 is a sectional plan on line A—A, Figure 1, and

Figure 3 is an enlarged sectional elevation of the cross piece.

The valve casing 1 provided with directly opposing nipples 2 and 3 adapted to be inserted in or attached to milk tubes of a 100 milking machine, is also provided with a hollow plug 4, in which a ball 5 is housed.

The plug has directly opposing ports 6 and 7 of different diameters, the larger port 6 having a cross wire 8 or the like to prevent the ball seating itself in, and closing the said port. The port 7 has a seat 9 for the ball 5.

The plug has a pin 10 which works between stops 11 on the casing, so as to limit the turning movement of the plug in the 10 casing to a half turn.

Projecting from the plug is a spring 15 pressed ball 12 adapted to engage in a circular groove inside the casing. The plug 4 which is capable of being drawn out of the casing from the top, is retained therein, while in use by the engagement of the ball 12 in the circular groove, the engagement 20 however not being sufficient to prevent the plug from being readily removed when desired.

A semi-circumferential groove 13 in the outer surface of the plug 4 connects or extends from the port 6 to the port 7, and another groove 14 extends from the groove 25 13 to the bottom of the plug 4.

A cap 15, having ports 16 and screwed upon the lower end of the casing 1, holds a ball 17 adapted to close upon a seating 17^a and close the lower end of the casing, 30 when the air is exhausted from the interior of the plug 4 and casing 1.

A cross piece 18 fitted into the lower end of the plug 4 has projecting downwards therefrom a pin 19 having a head 20 against 35 which a spring 21 presses. The ball 17 when on its seating 17^a pushes in the pin 19 and compresses the spring 21.

During milking operations the ball 17 is held on its seat 17^a by the vacuum and when 40 the vacuum is broken by a teat cup or cups coming off a teat or teats, the ball 17 assisted by the spring operated pin 19, opens the lower end of the casing to the atmosphere, thereby ensuring that the ball 5 will be 45 forced into its seating 9 and thereby prevent the entrance of air to the system.

The grooves 13 and 14 are provided to ensure that the ball 17 shall come under the effects of vacuum when required so as to 50 close on its seat 17^a and prevent entrance of air to the casing and plug.

The nipple 2 opposite the larger port 6 is adapted to be put into communication with the milk passage or passage of a teat 55 cup claw either by being rigidly connected to the claw, or by flexible tubing or tubing and pipes, while the nipple 3 is adapted to be connected by flexible tubing or pipes with a vacuum creating source.

To permit milking operations to proceed, 60 the plug is turned to bring the ports into register with the nipples, and so that the larger port 6 registers with the nipple 2.

With the teat cups in position on the teats 65 and milking operations proceeding nor-

mally, the ball remains below the ports 6 and 7 and the ball 17 closes on its seating 17^a, but should the teat cups fall off the teats, the angle which the valve assumes and the sudden drop thereof causes the ball 5 to jump in the plug 4 and the ball 17 leaves its seating 17^a whereupon the inrush of air through the ports 16 forces and holds the ball 5 against the seating 9, thereby preventing air sufficient to interfere with milking operations from entering the apparatus. 75

When the teat cups are replaced on the teats, the slight leakage allowed by the groove 13 enables the air in the passages on the teat cup side of the valve to be exhausted and on the pressure on each side of the ball 5 becoming equal the latter drops in the plug 4 and allows the milk to pass through the valve from the nipple 2 to the nipple 3. 80

When a set of teat cups is not being used 85 during milking the entrance of air can be completely shut off by giving the plug 4 a quarter turn.

If it is desired to flush the machine by drawing water through the same, the plug 90 4 is turned so that the port 6 with its wire 8 will register with the nipple 3, the result being that when the teat cups are immersed in water, the ball 5 does not interfere or prevent the entrance of the water to the system. 95

What I do claim and desire to obtain by Letters Patent of the United States of America is:—

1. A valve for the purpose described comprising a casing with opposing nipples, a 100 plug in the casing having a port adapted to register with the nipples, and a ball in the plug adapted to close one of the said nipples.

2. A valve for the purpose described comprising a casing with opposing nipples of 105 different diameters, a plug in the casing having a cross port adapted to register with the nipples, and a ball in the plug adapted to close the smaller of the said nipples.

3. A valve as claimed in claim 2, wherein 110 the ball is prevented by a wire from closing the larger nipple.

4. A valve as claimed in claim 1, the plug of the casing being made hollow with directly opposing ports of different diameters 115 and adapted to register with the nipples, a wire across the larger port and the smaller port having a niched seating.

5. A valve as claimed in claim 1, the nipples being of equal diameter, the plug being hollow and having opposing ports of different diameters adapted to register with the nipples, a wire across the larger port, and a groove around the plug adapted to connect the said ports. 120

6. A valve as claimed in claim 5, and having a groove connecting the groove around the plug to the bottom of the plug.

7. A valve as claimed in claim 5, and a cap having ports secured to the bottom of 125

the casing, and a ball in the cap adapted to seat upon the bottom of the casing.

8. A valve as claimed in claim 5, having a cross piece in the casing, a spring pressed 5 pin in the cross piece adapted to be operated by the ball in the cup when the said ball is closed upon its seating.

9. A valve as claimed in claim 7, having a cross piece in the casing, a spring pressed 10 pin in the cross piece adapted to be operated

by the ball in the cup when the said ball is closed upon its seating.

In testimony whereof I have signed my name to this specification in the presence of two witnesses.

SYDNEY HERBERT KNAPP.
